UNITED STATES PATENT OFFICE

2,548,882

WRINGER

Edwin E. Foster, Austin, Tex.

Application September 21, 1944, Serial No. 555,136

21 Claims. (Cl. 68—263)

1

This invention relates to wringers which are particularly adaptable for squeezing laundered and washed articles of all types and materials.

In its broad aspect the invention relates to a type of wringer having squeezing rolls which are arranged and operate vertically instead of horizontally and are relatively movable toward and away from each other. It is therefore an object of the invention to provide a wringer having vertically directed cooperating rolls which are adapted to squeeze water from wet textile materials and articles. Thus the vertical arrangement of the squeezing rolls eliminate the usual gear box or transmission member which is necessary in a wringer having horizontal rolls.

Another object of the invention resides in the provision of a table below the rolls of a wringer and a cone-shaped member mounted on the table to guide and maintain the articles to be squeezed toward and to the approximate central part of the rolls, that is from the ends as much as possible.

A further object of the invention resides in the provision of a flexible roll in which a plurality of elastic members are mounted to force the periphery of the flexible roll against or toward the other roll.

Another object of the invention resides in the provision of a plurality of knee-action rollers or wheels which latter roll on a flexible rubber sleeve so that this rubber sleeve will yield at such sections relative to other sections where the material to be squeezed is thicker thereby achieving a more uniformly distributed pressure. In conventional type rollers the latter tend to press too hard on the thickest portions of the materials, while the thinner portions along the edges, for instance, reabsorb and retain the water which has been squeezed out of the thick central portion. Thus a further object of the invention resides in the knee-action system in one of the rolls in order to squeeze the water out of the thin portions of the materials to be squeezed without applying excessive pressure on the thick portions.

Another aim of the invention resides in the specific structure of the squeezing rolls, both of which have flexible sleeves and of which one sleeve is driven or rotated by its axial internal sleeve and the other is driven or rotated by the first-mentioned sleeve. It is also an object of the invention to provide a wringer having a continuously rotating sleeve or member against which a flexible sleeve of one roll which is loosely mounted thereon is pressed or forced by the other sleeve or roll.

2

The invention also aims to provide a safety device or lever which is operative from any angle to immediately separate the rolls relative to each other. The lever is also directed vertically and can be contacted for movement in any direction.

Further objects will be apparent from the following description when considered in connection with the accompanying drawings in which:

Fig. 1 is a front elevation of the wringer,
Fig. 2 is a plan view with the rolls in section,
Fig. 3 is a sectional view taken on line 3—3 of Fig. 2 showing material being squeezed between the rolls,

Fig. 4 is a cross section taken on line 4—4 of Fig. 2,

Fig. 5 is a plan view with the rolls in open position,

Fig. 6 is a plan view of the wringer showing the rolls in a position to apply pressure,

Fig. 7 is a perspective view of the wringer, and
Fig. 8 is a bottom plan view of a portion of the wringer.

The wringer according to this invention may be provided and secured on a table or motor, not shown, or any other frame, device or fixture such as a washing machine where it may be desired to operate and mount the wringer. As shown a tubular post 1 fits over a vertical drive shaft post of a washing machine for instance, and is provided with an index finger 2. Fixed directly to the post 1 is a frame or base member 3, which is preferably of triangular shape, as shown by the dotted lines in Fig. 2. Concentric with the tubular member 1 is a vertical stationary tube 4 having two sleeve bearings 5 which are pressed onto this tube member 4, one at the lower end and one near the center part, Fig. 3. A rotating metal sleeve or tube 6 bears on the bearings 5 and is driven by means of a square hole (not shown) in its upper end by a torque shaft 7. The lower end of the torque shaft 7 is provided with an enlarged head, which includes a slot section 8, into which the drive shaft from the washing machine fits. The wringer is provided with a driving roll 57 and a larger driven roll 58, the latter of which is movable in a horizontal direction relative to roll 57. A rubber sleeve or tube 9 of roll 57, preferably having a convex rubber end 56, fits loosely about the tube 6. The rubber sleeve 9 rests on a table 10 and tends to remain stationary, the tube 6 and the torque shaft 7 revolving, except when pressure is applied through a second and larger roll, at which time the rubber sleeve revolves counter-clockwise, as shown in

45
50
55

Figure 2. A second rubber sleeve 11 of roll 58 is large enough to enclose a knee-action system and is also provided with an end section or closure 59 to prevent water from entering the sleeve and also for better appearance. Inside the sleeve 11, is a stationary vertical tube member 12, identical with the tube member 4. The tube 12 is fixed directly to the base member 3 and is strong enough to resist the pressure applied by a plurality of knee-action rollers 32. A movable tube member 13 telescopes over the stationary tube 12 and is connected to a smaller tubular member 14 at the upper end by means of a pin 15 and a spacer sleeve 16, shown in Fig. 3. The tubular member 13 is provided with arms 17 at each end and also several others, each between two knee-action rolls 32. A small shaft 18, on which knee-action fingers pivot, is supported by means of the arms 17 which are stamped out of the tube 13 before the tube is rolled. The torque tube 14 extends below the end of the stationary tube 12 and is provided with a cam plate member 19. The cam member 19 is provided with a latch which cooperates with a roller 20 and a push link 21, the latter being pivoted at 22 to a bell crank member 23, pivoted to the frame member 3, by means of a pin 24. The bell crank member 23 extends to the edge of the table 10 through the slot 25, shown in Fig. 1, and is provided with a ball handle 26. This handle 26 is operated to apply pressure between the rolls 57 and 58. The cam plate 19, which is fixed directly to the torque tube 14 is also provided with an arm section which includes a pin 27 connected with a tension link 28 which operates through a pin 29, an idle lever or link 30, the latter being loosely mounted on the pin 24.

The bell crank member 23 is provided with a projection stop 31, which abuts the idle link 30, as shown in Figs. 5 and 6. Each of the small hard rollers 32 is provided with a suitable bearing 33 and rotates on a pin 34, which is mounted between the sides of a U-shaped leg 35. This U-shaped stamped leg member 35 is provided with a web section 36 and a web section 37, Fig. 2, and it also has a sleeve member 38 pressed therein at the time a double torsion spring 39 is pre-loaded and trapped between the webs 36 and 37 and the sleeve 38.

As shown in Figs. 2 and 3, the open ends of the double torsion spring 39 abut against the web section 36 of the leg member 35, while the closed end abuts against the tubular member 13. As the knee-action rollers 32 react on the thickness of the material or clothes 60 to be squeezed the open ends of the double torsion spring 39, carried by the web 36, move about the pivot point 18 and the limit stop 37 moves away from the closed end section of the torsion spring.

In order to release the pressure between the rolls, it is necessary to touch and move a universally pivoted release bar 40 whereby the large roll 58 will pivot clock-wise about the stationary tube 12 to the position shown in Fig. 5. The release bar 40 is provided with a circular plate 41 at its lower end and is urged and held upward against the bottom of the table member 10 by means of a compression spring 42, which lifts against a cupped member 43 which is pinned to the release bar 40. When the bar 40 is moved in any direction, the central part of the disc 41 moves downward against a ball section 44 on the end of a bell crank lever 45 pivoted to the frame member 3 at the point 46. A lower arm 47 of the bell crank 45 is provided with a push link

48, which operates a lever 49 pivoted at the point 50. The push link 48 causes the lever 49 to push the roller 20 off the latch section of the cam plate 19 and allows the entire knee-action assembly, which is mounted on the tubular sleeve 13, to revolve about the stationary tube 12 to the position shown in Fig. 5. Since the double torsion springs 39 were preloaded and trapped by means of the limit stops on the leg member 35, the latch release will open quickly with very little noise. It may remain in its open position shown in Fig. 5, or rebound slightly.

In order to re-set the roll 58 and apply pressure, it is necessary to move the re-set knob 26 to the position shown in Fig. 6, whereby the roller 20 will snap into the latch on the plate 19 at the time the large roll 58 has almost touched the smaller roll 57. Then the knob 26 is moved back to the position shown in Fig. 2, which will cause the push link 21 to further revolve the plate 19 and the torque tube 14, together with the tube member 13, and apply pressure between the rolls. The limit stop 37 may move slightly away from the spring 39, but most of this initial pressure will be taken up in the give in the rubber sleeves 11 and 9.

A small raised section 51 is provided in the table at the point where the rolls come together, as shown in Fig. 2. This portion 51 of the table 30 is intended to keep the tail end of the clothes slightly above the table. A groove 52 is also provided in the table 10 to turn back any water that gets beyond the rolls. An upright shield 53 is provided to turn the clothes back towards a tub or other container (not shown) as the clothes come out of the rolls.

In order to guide the materials to be squeezed into the rolls 57 and 58 a tapered cone-shaped guide member 54 is mounted on the table 10 by suitable rivets and the like, Fig. 4, this member having an elongated configuration as shown in Figs. 2, 5 and 6. The member 54 may be formed from light weight sheet metal and it may be snapped onto the table by means of buttonhole 49 catches 55a or by other similar device. The guide member 54 could also be made integral with the table 10 but a removable member is preferred for cleaning purposes. The guide member 54 not only guides the clothes as they are drawn around this member and into the rolls but also it keeps the clothes from working down to the bottom of the rolls. After one article has been started through the rolls the next articles can be lapped across the end of the preceding article 55 which will be drawn into the rolls without the necessity of the operator having to place the fingers near the rolls themselves.

The handle 26, which operates in the slotted section 25 of the table 10, is held in the position 60 shown in Fig. 2 by means of a suitable notch (not shown) in the upper side of the slot in order to maintain the toggle member, composed of the link 21 and the bell crank 23 in a straight line position. Thus it is necessary to press the knob 65 26 downward a slight distance to release it from this latch. A tension spring 55, Fig. 3, holds the link 21 against the lever 49.

The wringer operates as follows:

The operator takes a position directly in front 70 of the machine as shown in Figs. 1 and 3, that is in front of the plane between the rolls 57 and 58, and slides the article or material to be squeezed between the rolls after which the rolls will pull 75 the material through the rolls with a squeezing

action. The material follows a path through the machine as indicated by the arrows and lines 60, Fig. 2, in the direction of the arrows, the material being deflected by the shield 53. As the material passes between the rolls the knee action wheels 32 accommodate the rubber sleeve 11 to the varying thickness as indicated in Fig. 3, which will result in the water being squeezed from the material. As shown the material passes over the cone 54, through the rolls and then is deflected by the shield 53 to the right thereof and finally over the edge of the table.

If for any reason it is desired to separate the rolls 57 and 58 it is only necessary to move the bar 40 in any direction which results in the central part of the disc 41 moving downward against the ball section 44 on the end of the lever 45. The arm 47 operates the push link 48 which in turn operates the lever 49, the latter causing the roller 20 to be moved off the latch section of the cam plate 19 to permit the entire knee action assembly to revolve around the tube 12 to the position shown in Fig. 5. The rolls are thus separated and since the springs 39 were pre-loaded and are held in such position by means of the limit stops on the leg member 35 the latch release will open quickly and remain open. In order to reset the roll 58 and apply pressure, the resetting knob 26 is moved to the position of Fig. 6 whereby the roller 20 will snap into the latch on the plate 19 when the roll 58 almost contacts the roll 57. Then the knob 26 is moved back to the position of Fig. 2 which causes the link 21 to further revolve the plate 19 and the tube 14 and tube 13 so that pressure is applied between the rolls.

The rotation of the sleeve 6 which is driven by any suitable motor or other suitable means causes rotation of sleeve 9 and the latter in turn rotates the rubber sleeve 11, the sleeves 9 and 11 rotating in the directions indicated by the arrows, Fig. 2. The water squeezed from the material runs off from the table 10.

The top of the guide 54 may be adjacent or near the roll 58 but it is preferable to space 45 guide 54 about one-half of an inch or more from the roll 58 in the event the material to be squeezed adheres to the rubber sleeve 11. As a preferred structure the guide 54 has a back edge which extends from the table 10 at 61 to the top 62 thereof along the length as seen in Figs. 5 and 6.

The drain channel 52 may extend toward the front of the machine so that the water which is squeezed from the material will not drain into a container arranged to receive the squeezed material. Thus, as shown in Figs. 5 and 6, the channel 52 may extend a short distance between the guide 54 and the edge of the table.

I claim as my invention:

1. A wringer comprising a horizontal table, a pair of squeezing rolls projecting above the table at right angles to the table, each roll having one end at the table and with the other end free, means for rotating one of said rolls, and means for adjusting the other roll away from and towards the driving roll thereby providing squeezing and open positions of the rolls, said driving roll having a rotating sleeve and a tube loosely fitting on said sleeve whereby when the other roll forces the tube against the sleeve, rotation will be imparted to said tube and the other roll.

2. A wringer comprising a horizontal table, a pair of rolls projecting vertically from the table of which one roll is a driving roll and the other

roll is driven by said driving roll, said driven roll comprising a flexible sleeve, and a plurality of knee action rollers mounted in the sleeve to permit the sleeve to accommodate the varying thicknesses of the material to be squeezed.

3. In a wringer, a squeezing device comprising a pair of rolls of which each roll has a flexible sleeve which is loosely fitted for rotation, means in one of said sleeves to rotate said sleeve and the latter in turn rotating the other sleeve, and a plurality of spring pressed rollers mounted within said other sleeve to permit the latter to accommodate the varying thicknesses of the material to be squeezed.

15 4. In a wringer, a squeezing device comprising a pair of rolls of which each roll has a flexible sleeve which is loosely fitted for rotation, means in one of said sleeves to rotate said sleeve and the latter in turn rotating the other sleeve, and a plurality of pivotally mounted members mounted within the other sleeve to flex the sleeve to conform to the varying thicknesses of the material to be squeezed.

25 5. A wringer comprising a pair of vertically disposed squeezing rolls, means for driving one of said rolls, means including a vertically disposed bar movable in a lateral direction and operatively connected to the other roll to move the other roll to open position away from the driving roll, and means for resetting the movable roll to a position in contact with the driving roll from the open position of the rolls.

35 6. A wringer comprising a horizontal table, a pair of squeezing rolls projecting above the table at right angles to the table, means for rotating one of said rolls, means for adjusting the other roll away from and towards the driving roll thereby providing squeezing and open positions of the rolls, and a cone-shaped guide member mounted on the table in front of and on the material entry side of the rolls.

40 7. A wringer comprising a horizontal table, a pair of squeezing rolls projecting above the table at right angles to the table, means for rotating one of said rolls, means for adjusting the other roll away from and towards the driving roll thereby providing squeezing and open positions of the rolls, a cone-shaped guide member mounted on the table in front of and on the material entry side of the rolls, and a curved plate mounted on the table on the side opposite the material entry to guide the material from the table.

8. A wringer according to claim 2, in which each knee-action roller is spring pressed to constantly urge its roller against the flexible sleeve.

55 9. A wringer according to claim 7, in which the table is provided with a raised section directly in front of the squeezing rolls to maintain the end of the material to be squeezed above the upper surface of the table.

60 10. A wringer according to claim 7, in which the guide member is removably mounted on the table and is elongated at the base portion away from the rolls.

65 11. In a wringer, a squeezing device comprising a pair of rolls of which each roll has a flexible sleeve which is loosely fitted for rotation, means in one of said sleeves to rotate said sleeve and the latter in turn rotating the other sleeve, and a plurality of pivotally mounted and spring pressed rollers in said other sleeve to permit the latter to be distorted with squeezing force to accommodate the varying thicknesses of the material to be squeezed.

12. A wringer according to claim 4, in which the means for rotating the sleeve includes a shaft extending into the sleeve and which rotates continuously and rotates its sleeve when the other sleeve exerts pressure thereon.

13. In a wringer, a squeezing device comprising a pair of rolls each in the form of a flexible sleeve which is loosely fitted for rotation, a continuously rotating shaft for one of the sleeves, a shaft for the other sleeve eccentrically mounted with respect thereto, and means within said other sleeve adjusting said other sleeve eccentrically around its shaft for causing relative movement of the sleeves toward and away from each other to open and close the wringer.

14. A wringer according to claim 13, in which a horizontally arranged table is provided for the rolls, the latter projecting from the table in a vertical direction.

15. A wringer comprising a horizontal table, a pair of squeezing rolls projecting vertically above the table, a guide member secured on the table in front of the rolls relative to the travel of the material through the rolls and extending vertically above the table, and an upright shield 25 behind the rolls to guide the squeezed material from the rolls and off of the table.

16. A wringer comprising a horizontal table, a pair of squeezing rolls projecting vertically above the table, a guide member secured on the table in front of the rolls relative to the travel of the material through the rolls and extending vertically above the table, an upright shield behind the rolls to guide the squeezed material from the rolls and off of the table, and a raised 35 section immediately in front of the rolls and extending above the table to guide the material between the rolls just above the table.

17. A wringer comprising a horizontal table, a pair of squeezing rolls projecting vertically 40 above the table, a guide member secured on the table in front of the rolls relative to the travel of the material through the rolls and extending vertically above the table, an upright shield behind the rolls to guide the squeezed material from the rolls and off of the table, and a rod

extending above the table and parallel with the rolls to act as a safety lever to permit separation of the rolls.

18. A wringer according to claim 15, in which the guide member is in the form of a cone shaped sheet metal member with an elongated sloping section extending away from the rolls.

19. A wringer according to claim 15, in which means are provided under the table to laterally move one roll away from the other.

20. In a wringer, a squeezing device comprising a pair of rolls of which one roll is a driving roll and the other is a driven roll provided with a flexible sleeve, and a plurality of spring pressed rollers mounted within the sleeve of the driven roll to permit the sleeve to accommodate the varying shapes and thickness of the material to be squeezed, each spring-pressed roller having a diameter which is smaller than the diameter of the sleeve.

21. In a wringer, according to claim 20, in which means are provided to move the sleeve and spring-pressed rollers away from the driving roll to open the wringer.
